UNITED STATES PATENT OFFICE.

HENRY R. SHIRLEY, OF ST. PAUL, MINNESOTA, ASSIGNEE OF ONE-HALF TO JAMES A. EERLIS, OF BOSSLAND, CANADA.

TEMPERATURE-ALARM APPARATUS.

1,110,580.

Specification of Letters Patent. Patented Sept. 15, 1914.

Application filed February 10, 1913. Serial No. 747,823.

To all whom it may concern:

Be it known that I, HENRY R. SHIRLEY, a citizen of the United States, residing at St. Paul, in the county of Ramsey and State of Minnesota, have invented new and useful Improvements in Temperature-Alarm Apparatus, of which the following is a specification.

The object of my invention is to provide a temperature alarm apparatus whereby an audible signal will be sounded upon an abnormal rise of temperature, and whereby a visual signal, such for instance as an annunciator, will be actuated to locate the point of abnormal temperature.

One of the objects of my invention is to provide means for sounding or otherwise signaling continuously, upon a maximum rise of temperature, and this feature of my invention embodies a device which will cause such continuous signal until it is displaced or broken.

A further object of my invention is to provide means for setting the device so that an alarm will be sounded upon a rise of temperature to any predetermined extent.

Other features of novelty of my invention will be more fully described in connection with the accompanying drawings, and will be more particularly pointed out in and by the appended claims.

In the drawings: Figure 1 is a front elevation of my invention. Fig. 2 is a side view thereof. Fig. 3 is a view of a part of the apparatus shown in Fig. 1, partly in elevation and partly in section. Fig. 4 is a view in elevation of an adjustable contact. Fig. 5 is another elevational view thereof. Fig. 6 is a sectional view on line 6—6 of Fig. 1. 40 Like characters of references designate similar parts throughout the different figures of the drawings.

As illustrated, a base 1 is provided on which a thermometer 2 is mounted. Adjacent the thermometer 2 suitable graduations 3 are provided on the base 1 and a casing 4 is mounted on said base and is connected with the upper end of the tube 2. A contact element 5 is disposed in the casing 4 and is provided with a shank 6 adapted to extend into the tube 2. In cases where the interior cross section of the tube 2 is circular I flatten or otherwise mutilate one face of the shank 6, as at 7, so as to provide a passage 8, between the shank and the inner

wall of the tube 2 for passage of the mercury upwardly in the tube 2. The head of said element 5 is elongated, as indicated at 9, and on one side thereof is provided a rack 10. I preferably provide a casing 4 having an interior cross section corresponding to the cross section of the head 9 which construction serves to prevent rotative movement of the contact element with respect to the casing but which permits longitudinal movement with respect thereto.

Means is provided for adjusting the contact element and such means may comprise an adjusting gear 11, adapted to engage the rack 10, and a spindle 12 therefor rotatively mounted in the casing 4. A suitable bushing of insulation, designated at 13, may serve as a bearing for the spindle 12 and the latter may be provided with a recessed head 14 whereby the spindle may be turned by a screw driver or like implement to adjust the position of the contact element 5.

Near the upper end of the tube 2 I provide a pocket 15 which is preferably extended downwardly so as to form a trap for the mercury which overflows into the pocket.

An audible signal 16 is provided, in the form of a bell, and a visual signal 17, in the form of an annunciator.

A circuit is provided including a source of current 18 from one pole of which a conductor 19 leads to and is connected with the contact element 5. A portion of the conductor 19 is coiled, as indicated at 20, to permit of up and down movement of the contact element 5. A suitable insulation 21 serves to insulate the conductor 19 from the casing 4. A branch conductor 22 leads to the pocket 15 and its terminal 23 extends thereinto in spaced relation with a terminal 24 of branch conductor 25. The other pole of the source of current is connected by conductor 26 with the bell 16 and therethrough by conductor 27 to the annunciator 17. From the annunciator 17 a conductor 28, connected with branch conductor 25, has its terminal 29 projecting into the tube 2 at a point slightly above a normal temperature, as indicated by the graduations 3.

With the contact element 5, adjusted as shown, circuit would be closed and the audible and visual signals would be actuated when the mercury rises to a temperature as

100. Circuit would be closed through contact elements 5, the mercury, terminal 29 and conductor 28 through the annunciator and bell through the source of current and 5 through conductor 19 to contact element 5. The signals would be actuated, in this event, until the temperature lowered so that the mercury would not be in contact with the element 5. In case of a fire or other cause 10 of a sudden and abnormal or maximum rise of temperature the mercury would move upwardly past the shank of the contact element, in passage 8, into the pocket 15 where it would close circuit through terminals 23 15 and 24 and branch conductors 22 and 25, respectively, and thence through the circuit as hereinbefore described. This would cause a continuous sounding of the bell signal until the base 1 was shipped so as to 20 cause the mercury to flow out of the pocket back into the tube 2 or until the pocket 15 was broken to discharge the mercury therefrom.

25 While I have herein shown and described one specific embodiment of my invention, I do not wish to be limited thereto except for such limitations as the claims may import.

I claim:

30 1. A temperature alarm apparatus comprising in combination, a thermometer, a contact element having a shank projecting into and closely fitting the interior of the tube of said thermometer and having a flattened portion forming with said tube a restricted passage to permit rising of the mercury in said tube along said shank, said tube having a pocket to permit overflow of the mercury therein, and a circuit including 35 a source of supply of current and a signal device with one terminal of the circuit connected with said contact element and the 40 other terminal disposed in the path of rise

of the mercury in said tube, and branch conductors from said circuit having terminals disposed in spaced relation with respect to each other in said pocket, said conductors being adapted to permanently close the circuit when the mercury rises to a predetermined point, substantially as described, and connections to the said branch conductors.

2. A temperature alarm apparatus comprising in combination, a thermometer, a contact element having a shank projecting into and closely fitting the interior of the tube of said thermometer and having a flattened portion, forming in conjunction with said tube, a restricted passage to permit the rising of the mercury in said tube along said shank, an adjusting device, means carried 60 by said shank for engaging said adjusting device, whereby the projection of said shank into said tube may be varied, a pocket in said tube to permit the overflow of the mercury into said pocket, a circuit including a 65 source of current supply and an indicating signal device, said circuit having one terminal connected with said contact element and the other terminal disposed in the path of rise of the mercury in said tube, branch conductors disposed in spaced relation with respect to each other in said pocket, said conductors being adapted to permanently close the circuit when the mercury rises to a predetermined point, and an audible signal device connected in conjunction with the aforesaid indicating signal device.

In testimony whereof I affix my signature in the presence of two witnesses.

HENRY R. SHIRLEY.
